MELTING POT

Albert H. Jung, Flushing, N. Y., assignor to United American Metals Corporation, Brooklyn, N. Y., a corporation of New York

Application April 28, 1939, Serial No. 270,634

7 Claims. (Cl. 266—33)

This invention relates to melting pots and more particularly to melting pots capable of supplying molten metal rapidly and economically to facilitate the casting of relatively large quantities thereof.

Prior to the instant invention, melting pots have had their burners or heating elements so associated therewith as to maintain the temperature of the molten metal at a level generally corresponding to the casting temperature and when relatively large quantities of molten metal are cast, a measurable period of time must elapse before additional solid metal may be melted or fed to the pot and its state changed from a solid to liquid, before additional metal may be used for casting. This necessary time delay associated with prior constructions has been found to be costly as the labor and overhead which must be charged to each casting is proportional to the time involved in the fabrication of each casting.

Other prior constructions have been designed to melt metal relatively rapidly but such constructions have been relatively large and necessarily costly and further by reason of their size have been wasteful of fuel especially during those times when casting takes place at a relatively slow pace.

It is an object of the instant invention to provide a relatively small size high capacity efficient melting pot.

It is a further object of the instant invention to provide a combined two compartment two temperature melting and serving pot.

Other objects and the nature and advantages of the invention will be apparent from the following description taken in conjunction with the accompanying drawings, wherein:

Fig. 1 is a vertical section of a melting pot in accordance with the invention;

Fig. 2 is a top plan view of the embodiment of the invention illustrated in Fig. 1, depicting the metal ingot being fed to the melting bath in section;

Fig. 3 is a sectional view taken along line 3—3 of Fig. 1;

Fig. 4 is a fragmentary sectional view illustrating the flue and its association with the furnace walls; and

Fig. 5 is a view similar to Fig. 1 but of a modified form of the invention.

Referring to the drawings the furnace 10 comprises a refractory lining 11 and a cap 12 of material which may or may not be of refractory substance but should be capable of withstanding high temperature. The combined melting pot 13

may be supported on this cap 12 by the integral flange 14 associated with the recess 15 and the cap 12.

The combined melting pot 13 may include the relatively small capacity, but deep, high temperature cavity 16 and a relatively large capacity but shallow serving cavity 17. The two cavities may be connected by the relatively small diameter integrally formed passage 18 which may be controlled by the adjustable restrictor element 19 associated with its support 20 in screw-threaded relation whereby it may be raised or lowered to effect increase or decrease of restriction of the passage 18.

A heating element 21 is associated with the exterior of the relatively high temperature cavity 16 of the pot 13 and is depicted in Fig. 1 as being located directly therebelow. Depending from the under side of the top wall of the pot 13 there is located between the cavity 16 and the cavity 17 a baffle member 22 cooperating with the remaining structure to prevent the direct passage of all the relatively hot gases emanating from the burner 21 to the exterior of the cavity 17.

Though the baffle 22 extends from the top wall of the pot 13 completely about the connecting passage 18 and depends therefrom, it does not contact the refractory lining 11 but is spaced therefrom on three sides; namely, the bottom side 23, see Fig. 1, the side 24, and side 25, see Fig. 2, to permit a predetermined proportion of the gases to flow about the exterior of the cavity 17 and convey heat to the molten metal therewithin. That portion of the refractory lining which is adjacent to the cavity 17 is built up to provide a predetermined hot gas passage size thereabout.

The gas burner 21 is supplied with fuel through the pipe 26 which is controlled by electro-magnetic valve 27 which in turn receives its energy from the source of current 28 when the switch 29 is in a closed position. The switch 29 is in turn controlled by the thermo-couple 30 which through relay 31 affects the operation of the same. The meter 32 mounted on the panel 33 may visibly register the temperature of the molten metal in the bath 34 within the cavity 17 and about the thermo-couple 30.

As the high temperature molten bath 35 communicates with the relatively low temperature molten bath 34 through the passage 18, under static conditions or substantially static condition, the level within the cavity 16 and 17 will be substantially the same. As metal is removed from the serving cavity 17 the level therein will drop

and the level within the cavity 16 will also drop. Associated with the high temperature bath 35 and directly above the cavity 16 is an ingot feeding mechanism 36 comprising a float 37 secured 5 to the mechanism by chain 38. When the level within the molten bath 35 is lowered, the float 37 drops, pulling chain 38 and releasing the feeding mechanism 36 to lower the feed hook *h* to which is attached the ingot 39 which may be of any 10 suitable type but is depicted as being an automatic slip-off ingot. Lowering of the ingot 39 within the molten bath 35 effects the melting thereof and the replenishment of the molten bath to raise its level and effect a corresponding raising 15 of the float 37 which slacks the chain 38 to cause cessation of operation of the feeder mechanism 36 until the level of molten metal is again lowered, at which time the cycle above described is repeated.

20 As the cavity 17 is much larger than the cavity 16, see Fig. 2, the lowering of the level of the former requires the melting of a considerable amount of metal to effect its replenishment. To melt the necessary amount of metal rapidly, the 25 molten bath 35 is maintained at a higher temperature than the molten bath 34, which latter temperature may be generally corresponding to the casting temperature. For example, if the casting temperature is approximately 700° F., the 30 temperature of the molten bath 34 may be maintained at that temperature whereas the temperature of the molten bath 35 may be permitted to reach 900° F. or even more. As the communicating passage 18 connects the high temperature bath 35 with the bottom of the lower temperature bath 34, the relatively high temperature molten metal passing to the molten bath 34 must diffuse upwardly and therethrough and thereby prevent undue rising of temperature in any one portion of 40 the molten bath 34.

Should the temperature of the molten bath tend to rise above a predetermined level of, for example, 2700° F., the thermo-couple 30 will cause the relay 31 to close the switch 29 and permit electric current to flow from the source 28 to the electro-magnetic valve 27 to effect closing the fuel line 26 and cause cessation of operation of the burner 21 whereupon the temperature of the molten bath 35 will drop somewhat, whereby 50 metal passing to the molten bath 34 through the communicating passage 18 will not transfer a maximum of heat to the bath 34 and further, there will be no flue gases about the exterior of the cavity 17 to transfer heat to the molten bath 34. When the bath 34 requires additional heat to maintain the temperature at the predetermined level which may be 700° F., the thermo-couple 30 will be so actuated as to generate sufficient current to hold the switch 29 down against 55 the action of the spring 31' whereupon the switch 29 will open and break the flow of current from the source 28 to the electro-magnetic valve 27 permitting the latter to fall open whereupon the fuel will pass through the line 26 and will be ignited by pilot 40. Flue gases from the burner 21 pass in intimate contact with the exterior of the cavity 16 to maintain the temperature of the molten bath 36 substantially above that of the molten bath 34 and then passes about the baffle 70 22 along its sides 23, 24 and 25 to about the exterior of the cavity 17 and thence out the flue 41. The flue 41 is arranged on the exterior of the furnace 10 but relatively remote from the front 42 where the operator may stand and ladle molten metal from the cavity 17 as desired.

Not only is the construction of the melting pot 13 and the furnace 10 such as to effect a higher temperature within the molten bath 35 than within the molten bath 34, in order to permit rapid casting without depleting the available molten metal, by effecting the rapid melting of the ingot by feeding it to the high temperature bath, but the adjusting element 19 is so aligned in association with the passage 18 as to slow down the lowering of the level within the molten bath 35 even though the level within the molten bath 34 is lowered rapidly corresponding to rapid casting. This control of flow from the molten bath 35 to the molten bath 34 permits a relatively high level of hot metal within the bath 35 to be maintained effecting rapid melting of ingot 39 and the molten metal will be replenished before the level therein has opportunity to be considerably lowered.

It will be understood from the above description that applicant has provided a melting pot system which may be relatively small in size but high in capacity and simultaneously economical of fuel whereby casting, or utilization of the molten metal produced, may be effected rapidly 25 without interruption of the rapid melting of the metal in proportions corresponding to the metal used to efficiently utilize the heat energy operating to the device.

While the heating element associated with the 30 metal furnace 10 has been described as a gas burner, it is to be understood that other heating elements may be incorporated in the furnace construction such as for example an electric heater. When an electric heater is utilized in place 35 of the burner 21, the control thereof is somewhat simpler as the electro-magnetic valve 27 may be eliminated, the source of current 28 directly associated with the electric heater, and the control of the source effected by the switch 29 which 40 is in turn controlled by the thermo-couple 30.

In certain casting processes in the field where an apparatus in accordance with the instant invention is utilized, it is essential that an additional burner be utilized in connection with the 45 low temperature compartment of the two compartment melting pot. For example, where the casting operations take place intermittently with relatively long periods of time elapsing between successive casting operations, the low temperature 50 compartment may not receive enough heat by reason of the fact that in the embodiment of the invention previously described the sole sources of heat are the flue gases from the single burner and the heat exchange from the relatively 55 hot molten metal in the high temperature compartment. When no casting operations are taking place there is no heat exchange from hot molten metal from the high temperature compartment and accordingly the low temperature 60 compartment may not receive enough heat, or if it does by reason of the fact that the thermo-couple will make the single burner operate as long as the low temperature compartment does not have enough heat, the system will operate 65 inefficiently. Accordingly, see Fig. 5, an additional burner 100 is provided in association with the cavity 17 and located within a well 101 within the refractory material 11 and directly below the cavity 17.

The burner 21 is located below the cavity 16 in the same manner as that illustrated in Fig. 1 and serves to heat the molten metal within the said cavity. The pilot 40 cooperates with the burner 21 and the pilot 102 cooperates with 75

the burner 101. In this embodiment of the invention a main fuel line 26 is connected to the branch fuel lines 26a and 26b respectively. The fuel line 26a independently cooperates with the burner 21 and the branch fuel line 26b independently cooperates with the burner 100. The electro-magnetic valve 27 controls the branch fuel line 26a and the electro-magnetic valve 103 controls the branch fuel line 26b.

Instead of controlling the valve 27 from the temperature within the molten bath 34, in this embodiment of the invention it is controlled by the thermo-couple T located within the molten bath 35 and the temperature of the molten bath 34 is controlled by the thermo-couple T'. The thermo-couples T and T' serve to control the switches S and S' through the medium of electro-magnets E and E', respectively. A source of current C serves to supply energy necessary to operate electro-magnetic valves 27 and 103, respectively. The master switch 104 controls the source of current C and the individual switches 105 and 106 serve to operate the individual temperature control circuits 107 and 108, respectively. The remaining equipment and apparatus in this embodiment to the invention is similar to that described in connection with Figs. 1, 2 and 3.

In operation, the molten baths 34 and 35 are maintained within the same temperature ranges as described in connection with the first embodiment of the invention, but the control is effected by a thermo-couple associated with each cavity and in those instances in which such abnormal operations occur as to involve long periods of time between successive casting operations, satisfactory efficiency will nevertheless result, the individual molten baths in the multiple compartment melting pot being maintained in the proper temperatures and the fuel consumption being relatively low.

It will be obvious to those skilled in the art that various changes may be made in this device without departing from the spirit of the invention and therefore the invention is not limited to what is shown in the drawings and described in the specification but only as indicated in the appended claims.

What is claimed is:

1. A melting and molten metal storage apparatus comprising: a furnace having a refractory lining, a heating element in said furnace, a shell adapted to hold molten metal supported by said furnace, said shell including a pair of cavities, the first of which is located directly above said heating element and the second of which is located in the path of flow of hot gases from said heating element whereby it may be heated indirectly by said heating element, and means for controlling said heating element in response to the temperature of molten metal within said second cavity, said first cavity being adapted to have solid metal fed thereto and melted therein, and restricted passage means communicating said cavities.

2. A melting pot comprising a relatively high temperature bath adapted to have solid metal fed thereto and melted therein, and a relatively low temperature bath adapted to have molten metal withdrawn therefrom, means for heating the relatively high temperature bath, means for passing molten metal from said high temperature bath into the bottom of the relatively low temperature bath whereby the hot molten metal in said high temperature bath may serve to

transfer heat to said low temperature bath, and control means for said heating means responsive to the temperature of said low temperature bath.

3. A plural compartment melting pot including a relatively deep cavity of small horizontal section adapted to have solid metal fed thereto and melted therein, and a relatively shallow cavity of great horizontal section adapted to have molten metal withdrawn therefrom, heating means directly associated with said deep cavity and indirectly associated with said shallow cavity, means for passing molten metal from said deep cavity into the bottom of said shallow cavity, whereby the molten metal in said shallow cavity will receive heat from the molten metal emanating from said deep cavity and passing upwardly through the shallow cavity and will also receive heat through its indirect association with said heating means.

4. The structure recited in claim 1, and means for adjustably restricting said passage means communicating said cavities.

5. A combined furnace and melting pot comprising a refractory lining, said refractory lining including a relatively small well, a burner in said well, a pair of molten bath cavities suspended within said lining, the first of said cavities being relatively small in horizontal section and located directly above said burner, the second of said cavities being located in a vertical plane distinct from said first cavity and said burner, means for passing molten material from said first cavity into the bottom of said second cavity, baffle means located between said two cavities and extending about said molten material passing means toward said refractory lining but being spaced therefrom to provide a restricted hot gas passage whereby hot gases from said burner may not only serve to heat said first cavity but they may also heat said second cavity, means responsive to the temperature within said second cavity for controlling said heating element, and means responsive to the level of molten liquid in said first cavity for feeding solid metal thereto.

6. A metal melting apparatus comprising a plural compartment melting pot, a first of said compartments being relatively deep but small in horizontal section, a second of said compartments being relatively shallow and large in horizontal section, means for passing molten material from said first deep compartment into the bottom of said second shallow compartment, means for restricting said passing means, a heating element located directly below said deep compartment for supplying a relatively great amount of heat thereto, restricting baffle means between said two compartments and in association with said heating element whereby most of the heat emanating from said heating element will be transmitted to said deep compartment, but some of said heat will be transmitted to said shallow compartment, said baffle means and said heat element tending to maintain the temperature of said deep compartment higher than the temperature of said shallow compartment, and means for maintaining the temperature of said shallow compartment within a predetermined range.

7. A metal melting apparatus comprising a furnace of generally circular horizontal section, a refractory lining about the interior of said furnace, said refractory lining being formed with a well adjacent one vertical wall thereof, a heating element located in said well, a plural compartment pot suspended within said furnace, a first of said compartments being relatively deep but

of small horizontal section and a second of said compartments being relatively shallow but of large horizontal section, said first compartment being located substantially directly above said 5 heating element, said first compartment being generally circular in horizontal section and said second compartment being generally kidney shape in horizontal section, means for passing molten material from an intermediate portion 10 of said deep compartment into the bottom of said shallow compartment, baffle beans depending from the under side of the top of said melting pot extending about said communicating means on all sides and generally between said two compartments in spaced relation thereto and further extending toward said refractory lining but 15

spaced from said lining whereby said deep cavity will be in direct heat exchange relation with said heating element and said shallow cavity will receive heat from said heating element indirectly from hot gases passing from the heating element 5 through the restricted passage between the baffle and the refractory lining to about the shallow compartment, a flue located on an exterior wall of said furnace adjacent said relatively small compartment, means for maintaining said shallow compartment within a predetermined temperature range, and means for feeding solid metal to said deep compartment in accordance with the level of molten liquid therein. 10

ALBERT H. JUNG.
